UNITED STATES PATENT OFFICE

WILLIAM P. QUENTELL, OF WASHINGTON, DISTRICT OF COLUMBIA

TYPEWRITING MACHINE

Application filed February 7, 1929. Serial No. 338,303.

This invention relates to typewriting machines and in particular to the mechanism which effects the bringing the type against the platen, and it is in line with my application for U. S. Patent Serial No. 330,232, filed January 4, 1929.

An object of the invention is to reduce the sound made by the impact of the type against the paper on the platen.

10 Another object is to relieve the operator of furnishing all the power to effect printing, and to employ outside power instead.

Another object is to simplify the construction of the mechanism by largely obviating 15 close allowances, thereby reducing the cost of manufacture.

In the accompanying drawings:

Figure 1 is an end elevation of a typewriting machine embodying the present invention.

Figure 2 is a longitudinal sectional view showing a key and corresponding type-carrier or typebar at normal position.

Figure 3 is a fragmentary view of Fig. 1, 25 but showing the typebar connecting with the power mechanism.

Figure 4 is a fragmentary view of the typebar and clutch mechanism at printing period.

Figure 5 is a front elevation with parts 30 broken away and showing a transverse section of the clutch and power transmission mechanism.

Figure 6 is an enlarged perspective detail 35 of the typebar rocker and parts comprising the rocker.

Figure 7 is a diagrammatic view of a typecarrier and the rocker, indicating the different arcs of travel of the type-carrier and the rocker.

40 Figure 8 is an enlarged detail of the clutch mechanism for connecting the rocker with the power source.

Figure 9 is a perspective detail of a part of the rocker carrying the clutch mechanism.

45 It is common practice in typebar writing machines to effect printing by bringing the typebar against the platen with a quick sharp motion; this is done by connecting the typebar very close to its pivot with key actuated connections, thus requiring little movement

or depression of the key. The quick smack of the type against the paper produces considerable sound and in order to reduce that sound I do not bring the typebar all the way to the platen by depression of the key with its 55 connections to the typebar near its pivot, but bring the bar only part way which locks the typebar to a rocker and then the rocker carries the typebar to the paper and presses it the required degree to print.

60 In the preferred construction I show the locking engagement between the rocker and the typebar near the type slug. By applying the power for printing impression to the typebar near the type, instead of near the pivot, the type is brought against the paper in a more controlled manner and in slower motion, and, as the pressure exerted by the power source is through cam action, the impact of the type against the paper is gradual 65 70 instead of sudden.

The foregoing and other objects of the invention, together with means whereby the same may be carried into effect, will best be understood from the following description of certain forms or embodiments thereof illustrated in accompanying drawings. It will be understood, however, that the particular construction described and shown has been chosen for illustrative purposes merely, and 75 that the invention, as defined by the claims hereunto appended, may be otherwise practised without departing from the spirit and scope thereof.

80 A is the frame or casing of a typewriting machine; B is a platen mounted in a carriage C; D is a key, Fig. 2, near the centre of the machine, there being the usual plurality of keys, though for clearness of illustration only one is shown. 1 is an arcual typebar segment in which are pivotally mounted the usual number of typebars, one of which, 2, is shown. Mounted on the arc segment 1 at its center is an upright flat post 3 provided with bent over portions 85 forming brackets 4, Fig. 2, which act as supports for a rocker 5 and its axis 6. The rocker 5 is formed with an extension 20 at the right side and at the extreme end 20^a of the extension it carries a clutch escapement, that 90 95 100

is, the parts that are part of the mechanism which connects and disconnects the rocker 5 with and from the power source. These parts I will term, for convenience, the clutch mechanism. It comprises a plate 21 fixed to the rocker extension 20, as at 20^a. This plate 21 has a rising portion with bent over lip 22 through which is mounted a pin 23. The lower end of the pin 23 has attached to it a spring 24. The pin is preferably of square section and threaded so that a nut 23^a in mesh with the screw thread will lower and raise the pin 23. The other end of the spring 24 is fastened to a lever 25 at lip 26. The lever 25 is pivotally mounted on a rod 6^a fixed to a bracket 26, the rod 6^a serving also as axis of the extension 20. The axis 6 and the axis 6^a being in line furnish a wide bearing for the rocker 5. The lever 25 is held against a stop pin 27 on plate 21 by the spring 24. The lever 25 carries a pin or, in preferred construction, an antifriction roller 28 at its free end. A shaft 30 to which is fixed a constantly running ratchet wheel 31 supports a loose disk 33 having a cam or, in preferred construction, a cam groove 34 on its side adjacent the lever 25. The roller 28 projects into the cam groove 34. The disk 33 has an extension 35 on which is pivotally mounted a pawl 36, Fig. 6. The pawl is in line with the ratchet wheel 31 and is tensioned by a spring 38 to engage the teeth 31^a of the ratchet wheel, but is held out of engagement and against a stop pin 39 as explained hereinafter.

A post 40 rises to the left of the plate 21 from the base of the machine and carries on its upper end at 41 a pivoted segment 42 held by a spring 43 against a stop pin 44 in the post 40. The segment 42 carries a pawl 45 pivoted at 46 and held against a stop pin 47 by a spring 48. The segment 42 has a portion 49 bent outward and to the plane of the ratchet wheel 31; this bent portion or finger is normally in contact with the part or finger 37 of pawl 36 and holds the pawl 36 out of engagement with the ratchet teeth 31^a.

The parts are at normal in Figs. 1 and 2, and in the enlarged detail Figs. 6 and 8. The rocker 5 is forward and away from the platen B, a spring 5^a attached to the rocker at 5^a and to the post 3 holding the rocker 5 against the extension or finger 3^a of post 3. The type-carrier 2 is pivoted at 106 on the segment 1 and is controlled by its corresponding key D through an intermediary link 102 pivoted on a transverse rod 104; link 102 is connected to the heel of the type-carrier 2 by a link 103 and to the key lever 101 through a link 100. The key lever 101 is pivoted on a transverse rod 102. A spring 105 holds the key lever and the connected parts, just described, at normal and returns those parts to normal after the key D has

been depressed and released. The typebar 2 is provided with a hook portion 2^c near the type slug, the portion 2^c being the free wall of the hook and 2^b the space between the bar 2 and portion 2^c. The rocker 5 is of such thickness that the upper edge 5^f will slide freely into the slot 2^b of the typebar. 70

Operation: When the key D is depressed it swings the type-carrier member 2 towards the platen B as is common in typebar machines, but before the type gets to the platen the typebar 2 strikes the rocker member 5 at the latter's top edge 5^f and as the type bar and rocker move towards the platen, the rocker will slide up into the slot 2^b of the typebar, 80 Fig. 3 and Fig. 7, owing to the axes of the typebar and rocker being so arranged as to make the travel arc of the typebar downward and that of the rocker upward after the two parts have come together. The typebar and the rocker are thus locked to one another, and, as the rocking of the rocker has caused the clutch to engage the constantly running power ratchet 31, the latter will cause the rocker to be rocked still more towards the 90 platen and cause printing impression to be made, Fig. 4 as will be explained now.

The plate 21 has an extension 22^a at its top which engages the pawl 45 on the segment 42, thus when the rocker 5 is rocked through depression of the key D, as described, the extension 22^a swings the segment 42, through its engaging pawl 45, rearwardly, thereby causing the finger 49 of the segment 42 to slip away from the part 37 of the pawl 36, and then the spring 38 will snap the pawl 36 into engagement of teeth 31^a of the motor driven ratchet wheel 31. 100

The cam disk 33 is thus connected to the running ratchet wheel 31 and rotates with it. As the roller 28 carried on lever 25 is always in engagement with the cam groove 34 it is depressed through the rotation of the cam; through such depression it rocks the rocker 5 which rocks towards the platen B and impresses the type 2^a against the paper B^a on the platen to print. 110

To prevent repeated impressions being made, should the operator keep the key D depressed, the extension 22^a, after moving the segment 42 far enough to free the pawl 36 from the finger 49, slips away from and under the pawl 45, and the spring 43 brings the segment 42 back to normal while the rocker part 22^a can remain in rocked position 120 as shown in Fig. 4.

As the cam disk 33 is brought around to its normal position in its rotation with the power wheel 31, the arm 37 of pawl 36 will strike the finger 49 of segment 42 and lift the pawl 36 out of contact with the tooth of the ratchet wheel 31 with which it was in engagement and the disk 33 will be locked against further forward movement. When the rocker extension 22^a returns to normal with the 130

rocker 5 it will "feather" or lift the pawl 45 and pass under it without disturbing the segment 42.

As the rocker 5 and typebar 2 are returning to normal position through motion from the power source, or through the spring 5^e drawing the rocker away from the post 3, the rocker will slide out of the hook 2^e and the typebar will be free to return to its normal position under tension of the spring 105.

In order to effect a desired strength of printing impression, as well as to eliminate necessity of close adjustments in the clutch mechanism, the lever 25 which carries the roller or pin 28 and is part of the mechanism which rocks the rocker 5 after the power wheel is connected to the mechanism, is held in normal position to the plate 21 by spring 24 so that the plate 21 and lever 25 move as one, but when the type 2^a is pressed against the platen before the roller 28 has been depressed to the extreme low point of the cam 34, the lever 25 will give and avoid undue strain on the parts of the mechanism.

By adjusting the tension of spring 24 through nut 23^a light or heavy impression can be made in printing.

With this invention the operator need use only sufficient force to depress the key far enough to move the typebar part of the distance towards the printing point, namely to the rocker when the power source will cause the typebar to complete the printing movement.

What I claim is:

1. In a typewriting machine the combination of a pivotally mounted type-carrier member, a rocker member for propelling the typecarrier member to print, one of said members being provided with a hook portion, the other member being provided with a contact portion for engaging said hook portion, the point of engagement being near the type end of the type-carrier member, the axes of said type-carrier member and said rocker member being so located that when the type-carrier member and the rocker member are brought together and moved together in one direction, the contact portion of the one member will enter the hook portion of the other member and lock the two members to one another so that the two members will move together at substantially the same speed to effect printing.

2. In a typewriting machine the combination of a pivotally mounted type-carrier member, a rocker member for propelling the typecarrier member to print, one of said members being provided with a hook portion, the other member being provided with a contact portion for engaging said hook portion, the point of engagement being near the type end of the type-carrier member, the axes of said type-carrier member and said rocker

member being so located that when the typecarrier member and the rocker member are brought together and moved together in one direction, the contact portion of the one member will enter the hook portion of the other member and lock the two members to one another so that the two members will move together at substantially the same speed to effect printing, and a key for effecting the type-carrier member and the rocker member being brought together.

3. In a typewriting machine the combination of a pivotally mounted type-carrier member provided with a hook near the type end of the type-carrier member, a rocker member for propelling the type-carrier member to print provided with a contact portion for engaging said hook, the axes of the typecarrier member and the rocker member being so located that when the two members are brought together and moved together in one direction, the rocker member will enter the hook of the type-carrier member causing the two members to become locked to one another and move at substantially the same speed to effect printing.

4. In a typewriting machine the combination of a pivotally mounted type-carrier member, a rocker member for propelling the typecarrier member to print, a power source, one of the members being provided with a hook portion, the other member being provided with a contact portion for engaging said hook portion, the point of engagement being near the type end of the type-carrier member, the axes of said type-carrier member and said rocker member being so located that when the type-carrier member and the rocker member are brought together and moved together in one direction, the contact portion of the one member will enter the hook portion of the other member and lock the two members to one another and cause them to move at substantially the same speed to effect printing, and means for connecting the power source with the rocker member to effect printing.

5. In a typewriting machine the combination of a pivotally mounted type-carrier provided with a hook portion near the type end of the type-carrier, a rocker for propelling the type-carrier to print provided with a contact portion for engaging said hook portion, a power source, the axes of the typecarrier and the rocker being so located that when the type-carrier and rocker are brought together and moved in one direction, the contact portion of the rocker will enter the hook portion of the type-carrier and cause the type-carrier and the rocker to become locked to one another, and move together at substantially the same speed to effect printing and means for connecting the power source to the rocker to effect printing.

6. In a typewriting machine the combina-

tion of a pivotally mounted type-carrier member, a rocker member for propelling the type-carrier member to print, a power source, one of the members being provided with a hook portion, the other member being provided with a contact portion for engaging said hook portion, the point of engagement being near the type end of the type-carrier member, the axes of said type-carrier member and said rocker member being so located that when the type-carrier member and the rocker member are brought together and moved together in one direction, the contact portion of the one member will enter the hook portion of the other member and lock the two members to one another, a key and connections for bringing the type-carrier member and the rocker member in contact with one another and thereby connecting the power source with the rocker member to effect printing.

7. In a typewriting machine the combination of a pivotally mounted type-carrier provided with a hook portion near the type end of the type-carrier, a rocker for propelling the type-carrier to print provided with a contact portion for engaging said hook portion, a power source, the axes of the type-carrier and the rocker being so located that when the type-carrier and rocker are brought together and moved in one direction, the contact portion of the rocker will enter the hook portion of the type-carrier and cause the type-carrier and the rocker to become locked to one another when moving together in one direction, and a key for bringing the type-carrier and the rocker together and thereby connecting the power source to the rocker to effect printing.

8. In a typewriting machine the combination of a platen, a type-carrier, a power source, a key for propelling the type-carrier part way towards the platen and means intermediate the type-carrier and the power source for propelling the type-carrier to the platen, said means comprising a hook portion on said type-carrier near the type end of the type-carrier and a rocker for engaging said hook portion thereby causing the type-carrier and the rocker to become locked to one another when moving in one direction, and means for connecting the power source with the rocker at predetermined period.

9. In a typewriting machine the combination of a platen, a type-carrier, a power source, a key for propelling the type-carrier part way towards the platen and means intermediate the type-carrier and the power source for propelling the type-carrier to the platen, said means comprising a hook portion on said type-carrier near the type end of the type-carrier and a rocker for engaging said hook portion thereby causing the type-carrier and the rocker to become locked to one another when moving in one direction and means for connecting the power source with

the rocker at predetermined period to propel the type-carrier to the platen to print.

Signed at Washington, in the District of Columbia February A. D. 1929.

WILLIAM P. QUENTELL.
